(57) **CLAIM**

I claim the ornamental design for a hockey skate laces simulating hat, as shown and described.

DESCRIPTION

FIG. 1 is a top plan view of a hockey skate laces simulating hat showing my new design;

FIG. 2 is a bottom plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The dotted lines on the laces forming a striated pattern form part of the claimed design. The finely-incremented dashed lines on the interior of the hat in FIGS. 2 and 5 illustrate environmental structure that forms no part of the claimed design.
